Patented Jan. 21, 1919.

UNITED STATES PATENT OFFICE.

ARTHUR E. JACOBS, OF CLEVELAND, OHIO.

COMBINED REGISTER AND ADDING MACHINE.

1,291,907.

Specification of Letters Patent.

Patented Jan. 21, 1919.

Application filed April 2, 1915. Serial No. 18,654.

To all whom it may concern:

Be it known that I, ARTHUR E. JACOBS, a citizen of the United States, and resident of Cleveland, in the county of Cuyahoga and State of Ohio, have invented certain new and useful Improvements in Combined Register and Adding Machines, of which I hereby declare the following to be a full, clear, and exact description, such as will enable others skilled in the art to which it appertains to make and use the same.

The objects of the invention are to provide improved tripping and advancing mechanism for operating the dogs, which actuate the adding wheels and dials of an adding machine and are indicated herein as improved mechanism to be employed in the operation of a cash register for ordinary mercantile business, combined with an adding attachment, such as shown and described in an application for Letters Patent filed by me June 30, 1914, and bearing Serial No. 848,116, in which the adding dogs are actuated by means of a curved plate to which a series of cam shaped extensions are secured, each dog in succession being actuated by one of these cam extensions.

To simplify the construction and to provide practical and efficient mechanism for this purpose, the mechanism including a main cam shaft and series of cams spaced thereon and inclined in a graduated series of angles is employed for this purpose, to operate the dogs.

The invention further includes means for rotating the shaft in one direction only so as to apply the cams in succession to the dogs which actuate the adding ratchets.

It further includes the combination and arrangement of parts and construction of details as hereinafter described, shown in the accompanying drawings and specifically pointed out in the claim.

In the accompanying drawings Figure 1 is a transverse section of the machine; Fig. 2 is a broken rear elevation, the rear wall being removed; Fig. 3 is a detail view of the ratchet and pawl mechanism which drive the cam shaft; Fig. 4 is a rear elevation of one of the operating dogs for the adding ratchets.

In these views the general portions of the machine remain unchanged including finger operated mechanism for the counting or sales dials, the exterior operating lever and adding dials, operated thereby, also

other details operated by the exterior lever for returning the finger operated levers to their places, which action also returns the sales dials to their first positions, and also serves to operate the adding dials to disclose the total sales made and previously indicated upon the sales dials.

These general features having been described in my previous application, do not require more than a slight description herein.

H, H, are a series of adding dial wheels loosely mounted upon a shaft G⁸ and operated simultaneously with the return movement of the respective finger levers by means of the following mechanism.

The dials are read through openings H', H' in the casing A. Each finger lever B is provided with a spring pressed pawl B³ which engages the teeth of a main ratchet wheel I provided with 60 teeth, which moves when actuated by its corresponding lever with the number of digits through which the finger levers moves.

Each ratchet wheel I serves as a spur gear to engage and operate a second gear I', which is attached to and in turn rotates one of the adding dials. Each adding dial contains three series of digits (each numbered from 0 to 9 respectively) and does not rotate backward but moves constantly in the same direction, so that when the digit 9 in one series of digits is passed the 0 of the next succeeding series appears.

These adding dials and main ratchet wheels are manually operated by means of the upward movement of the finger levers, which is obtained by moving the exterior lever forward, and all but the first dial are automatically operated, each by the movement of the next preceding ratchet wheel I to advance one digit in the scale of numbers, thus adding 10, 100, 1000, etc., in turn to the total sum obtained at the time that the exterior lever is moved back to its starting point.

This result is accomplished by special tripping and advancing mechanism constructed to operate as follows:

A tripping ratchet wheel J is secured to and turns with each main ratchet wheel I, and they are connected by means of a sleeve J⁸ loosely mounted upon the shaft C. The tripping ratchet wheel is provided with six teeth J², J², which are arranged to engage at every tenth space (equivalent to the series

of digits upon the adding and sales dials), with a tripping pawl J^3 pivoted upon a shaft J^4 , and to elevate the same to release a spring pressed pivoted arm J^6 .

5 This pawl J^3 is provided with a shoulder J^{20} which engages the extremity J^6 of the pivoted arm J^6 upon a shaft J^{10} . A spring operated pawl J^7 pivoted on this arm engages with the main ratchet wheel I which 10 operates the next succeeding adding wheel.

It is understood that each set of main and tripping ratchet wheels are connected together in pairs and that one pair will operate the next succeeding pair of ratchet 15 wheels, and thereby the corresponding gear and adding dial.

Each adding dial H and its respective gear I' are secured upon a common sleeve and gears and dials operate in pairs together. When held by the tripping pawl in 20 the position shown in Fig. 1 the spring pawl J^7 is not operating the teeth of the main ratchet wheel. But when the tripping dog J^8 is raised to drop the arm J^6 a roller 25 J^9 comes into engagement with a cam secured with others of a series of cams upon a common shaft K'.

These cams are arranged to pass entirely 30 out of engagement with the rollers J^9 on the forward movement of the exterior lever G^7 , but to engage in turn with the rollers J^9 upon the arms J^{20} and to release the tripping dogs J^3 when the exterior lever G^7 is 35 raised upon the rearward or return movement thereof.

This acts to remove each spring pawl J^7 in turn into engagement with the main ratchet wheel and to move the ratchet wheel the distance of one tooth as the cam moves 40 backward, which advances the corresponding dial the space of one digit.

The means for rotating the cam shaft in one direction to engage the tripping mechanism when the exterior lever is raised is 45 shown in Figs. 1 and 2.

Here K' is a gear loosely mounted upon

the shaft K^{11} and K^3 is a pawl upon said gear. This pawl engages a shoulder K^4 upon a disk K^5 fixed upon the shaft.

A segmental rack L upon an arm L' 50 integral with the arm G' and pivoted upon the shaft C, is operated by means of a link G^2 pivoted in the gear I and the shaft G^8 , and gear G^6 and shaft G^6 , to which the main lever G^7 is secured. 55

The pawl and ratchet mentioned permits the tripping cams K to operate in one direction only and to remain quiet during the interval.

The advancement of the adding dials for 60 the purpose of addition is obtained by the return or rearward movement of the exterior lever. These movements are made to alternate in this manner so that the adding dials 65 will remain quiet before the tripping and advancing movements begin.

A dog J^{15} for each main ratchet wheel prevents backward movement thereof.

What I claim as new and desire to secure by Letters Patent is:

The combination in an adding machine, 70 with main gears and tripping wheels secured thereto in pairs, of a tripping exteriorly projecting lever, a segmental rack operatively connected therewith, a cam shaft and 75 rigid cams thereon, said cam shaft rotated by said rack, a series of advancing spring dogs operated in sequence by said cams, each dog engaging one of said main gears, an extended rock arm upon which each dog is 80 pivoted, and an opposite arm rigidly connected therewith, a tripping lever engaging 85 with each arm, said tripping levers released by said tripping wheels in turn, and return springs for said dog supporting rock arms.

In testimony whereof, I hereunto set my hand this 19th day of October, 1914.

ARTHUR E. JACOBS.

In presence of—

RALPH W. JEREMIAH,
WM. M. MONROE.
